BIRD HOUSE

William J. Henreid, 8744 N. Oketo Ave.,
Niles, Ill. 60648

Filed Jan. 23, 1969, Ser. No. 15,463

Term of patent 14 years

Int. Cl. D30—01

U.S. Cl. D30—3

The single figure is a perspective view of a bird house embodying my new design.

The undisclosed side of the birdhouse is substantially the same in appearance as the side shown, and the rear is constructed like the front except that the wall is solid and there are no attachments.

I claim:

The ornamental design for a bird house, substantially as shown and described.
